DEVICE FOR TRUING FACE GRINDING WHEELS

Andrew J. Bryant, Cincinnati, Ohio

Application June 15, 1953, Serial No. 361,535

6 Claims. (Cl. 51—168)

1

This invention relates to an improved truing device for setting the diamond surface of a face type grinding wheel in precise balance with its face in a plane at right angles to the axis of the wheel spindle.

An object of the invention is to provide a truing device which cooperates with a conventional grinding wheel mount to balance any one of a number of types and sizes of face grinding wheels that may be secured on a spindle by means of said mount.

Another object of this invention is to provide a truing device for face type grinding wheels that has an extremely fine adjustment and which is automatically and effectively locked in adjusted position during rotation of the wheel.

A further object of the invention is to provide for a truing device of the foregoing character a safety guard which will eliminate the hazard of accidental loss of adjustment parts during operation of the grinding wheel.

With these and other objects in view the invention consists in certain constructions and arrangements of parts that shall be hereinafter fully described and pointed out in the appended claims.

In the accompanying drawings which illustrate the preferred embodiment of my invention:

Fig. 1 is a front elevation of a face type grinding wheel provided with the truing member of this invention.

Fig. 2 is a section taken on line 22 of Fig. 1.

Fig. 3 is a section taken on line 3—3 of Fig. 2.

Fig. 4 is a section similar to Fig. 3 showing the ring guard in a wheel adjusting position.

Fig. 5 is a perspective view of the ring guard.

With reference to the drawing the numeral 10 indicates the usual face type grinding wheel conventionally mounted on a rotatable spindle 11 by an adaptor 12. The adaptor has a tapered bore 13 which receives the tapered end 14 of the spindle 11, the adaptor being secured on the spindle by means of a pull-up nut 15 countersunk in the adaptor and threaded at 16 on the end of the spindle. The adaptor has an annular flange 17 at one end and is provided at its opposed end with external threads 18 which form cooperative means for mounting various sizes and types of face grinding wheels on the spindle. As best shown in Fig. 2 the grinding wheel has a central arbor 19 which closely fits the adaptor, the wheel being secured thereon by a washer 20 and a nut 21, the latter being threaded to the external threads 18 of the adaptor. The grinding wheel has a relatively thin circular web

2

200 that has an annular diamond cutting surface 220 formed around the front face of its peripheral portion.

The truing member of this invention is generally indicated by the reference numeral 22 and as best shown in Fig. 2 is preferably mounted on the adaptor between the flange 17 and the back face of the grinding wheel 10. The member essentially comprises an annular body portion 23 provided with a central aperture 24 that has a slip fit connection with the adaptor. A rearwardly extending, annular shoulder 25 is integrally formed on the outer peripheral portion of the body 23, said shoulder extending rearwardly from the truing device body and overlapping at least a part of the annular flange 17. A number of radially extending, threaded bores 26 are formed in the member and are preferably positioned therein such that they are partially in the annular shoulder 25 and partially in the body 23 of the truing device, said bores each being adapted to receive a wedge element that preferably takes the form of cone pointed set screw 27. As best shown in Fig. 2 the cone point of the set screws engage against the forward outer edge of the flange 17 and to the better accomplishment of this end the said edge is preferably ground to an inclined surface corresponding to the taper provided the cone points of the set screws.

To true the grinding wheel after it has been mounted on the spindle it is only necessary to insert a wrench into one or more of the hexagonal sockets of the proper set screws then turning them down to advance the particular set screws radially inwardly until a precise adjustment is made such that an instrument will indicate that the diamond face of the wheel is in a plane at right angles to the axis of the spindle 11. A very fine adjustment can be made because the effective axial movement of each set screw is decreased by the inclined engagement of the cone point with the flange 17. Further the connection between the cone and the flange creates considerable friction thus effectively locking the set screws against the flange during operation of the wheel.

My truing member may be provided with a means for retaining the set screws within the truing member so that loose, unused set screws will not become accidentally detached from the device during operation of the wheel. The retainer consists of a ring 28 which snugly encircles the truing member and is provided with a number of openings 29 which in wheel ad-

justing position will be in registry with the set screws so that a wrench may be inserted therethrough into the socket parts of the screws.

The ring is rotatably secured in position on the truing member by forming an annular groove 30 in the central part of the peripheral face of the member whereby the groove intersects the bores 26 formed therein. The groove freely receives a number of detents 31 extending inwardly from the central part of the retainer ring. As best shown in Fig. 5 each detent is formed in the ring by making a pair of parallel slits 32 in the body of the ring and then driving the ring body portion between the slits inwardly into the groove after the ring has been placed in position on the member.

There will be times when only one or two of the set screws need be adjusted to bear against the annular flange 17 of the adaptor to bring the wheel into precise balance. Under these conditions the unused set screws are liable to be turned from their bores during operation of the wheel. With the retaining ring of this invention in place these set screws will not become detached from the truing device even though the retainer ring is not moved to the effective guarding position shown in Fig. 3 after adjustment of the set screws. Automatic closing of the ring is secured by the initial acceleration of the grinding wheel which will cause the ring to slip relative to the truing device brought about by the inertia of the ring. The ring will continue to turn until the detents 31 come in contact with one or more of the screws in which position the openings 29 in the ring are out of registry with the set screws.

What is claimed is:

1. In a device for truing a face type grinding wheel operatively mounted on a rotatable spindle between an annular flange fixed on an intermediate part of the spindle and a draw up, wheel fastening means removably secured to the end of the spindle the combination of an annular truing member mounted concentrically on the spindle in engagement with a side of the wheel, said member having a peripheral shoulder overlapping at least a portion of the spindle flange, a circular row of radially adjustable devices carried by the shoulder, and each of said devices having a tapered inner end for operative engagement with the adjacent face of the spindle flange.

2. A device for truing a face type grinding wheel as set forth in claim 1 characterized by the fact that the radially adjustable devices are cone pointed set screws threaded in radial bores formed through the shoulder of the annular truing member.

3. A device for truing a face type grinding wheel comprising an annular member concentrically mounted on the wheel spindle in engagement with the non-grinding face of the wheel, a circular row of radially operative wedge elements carried by the annular member, and means for adjusting the radial positions of each of the wedge elements.

4. In a device for truing a face type grinding wheel operatively mounted on a rotatable spindle between an annular flange fixed on an intermediate part of the spindle and a draw up, wheel

fastening means removably secured to the end of the spindle the combination of an annular truing member having a circular body portion provided with a central aperture slip fitted on the spindle, an annular shoulder formed on the peripheral portion of the circular body portion of the member, said shoulder overlapping at least a portion of the spindle flange, a circular row of radially extending threaded bores formed through the shoulder, and cone pointed set screws threaded in the radial bores with the points in operative engagement with the forward face of the annular flange.

5. In a device for truing a face type grinding wheel operatively mounted on a rotatable spindle between an annular flange fixed on an intermediate part of the spindle and a draw up, wheel fastening means removably secured to the end of the spindle the combination of an annular truing member having a circular body portion provided with a central aperture slip fitted on the spindle, an annular shoulder formed on the peripheral portion of the circular body portion of the member, said shoulder overlapping at least a portion of the spindle flange, a circular row of radially extending threaded bores formed through the shoulder, cone pointed set screws threaded in the radial bores with the points in operative engagement with the forward face of the annular flange, and a retainer ring encircling the annular member, and having apertures formed therethrough positioned for registry with the set screws in the annular member, means for rotatably mounting the ring on the member, and ring stop means on the annular member effective to locate the apertures in the ring in nonregistering position with respect to the set screws upon relative movement between the ring and the annular member.

6. In a device for truing a face type grinding wheel operatively mounted on a rotatable spindle between an annular flange fixed on an intermediate part of the spindle and a draw up, wheel fastening means removably secured to the end of the spindle the combination of an annular truing member having a circular body portion provided with a central aperture slip fitted on the spindle, an annular shoulder formed on the peripheral portion of the circular body portion of the member, said shoulder overlapping at least a portion of the spindle flange, a circular row of radially extending threaded bores formed through the shoulder, cone pointed set screws threaded in the radial bores with the points in operative engagement with the forward face of the annular flange, and a retainer ring encircling the annular member, and having apertures formed therethrough positioned for registry with the set screws in the annular member, an annular groove formed in the annular member and intersecting the threaded set screw receiving bores formed in the member, and a number of detents punched in the retainer ring and extending into the groove, said detents being adapted to engage against the set screws to fix the operative position of the retainer ring with the apertures therethrough out of registry with said set screws.
